US0D1005806S

(12) **United States Design Patent** (10) **Patent No.:** **US D1,005,806 S**
(45) **Date of Patent:** **** Nov. 28, 2023**

(54) **LAWN AERATOR**

(71) Applicant: **Kun Zhang**, Shenzhen (CN)

(72) Inventor: **Kun Zhang**, Shenzhen (CN)

(73) Assignee: **Kun Zhang**, Shenzhen (CN)

(**) Term: **15 Years**

(21) Appl. No.: **29/910,947**

(22) Filed: **Aug. 27, 2023**

(51) LOC (14) Cl. **08-01**

(52) U.S. Cl.

USPC **D8/1**

(58) **Field of Classification Search**

USPC D8/1, 5-9, 61, 64-65, 70, 499

(57) **CLAIM**

The ornamental design for a lawn aerator, as shown and described.

DESCRIPTION

FIG. 1 is a front perspective view of a lawn aerator, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the lawn aerator, which form no part of the claimed design.

1 Claim, 8 Drawing Sheets
